Primary Examiner — Elizabeth J Oswecki(57) **CLAIM**

The ornamental design for a top shell of a helmet, as shown and described.

DESCRIPTION

FIG. 1 is a perspective view of a top shell of a helmet showing our new design, in a used condition with a helmet shown in broken lines;

FIG. 2 is a front perspective view thereof;

FIG. 3 is a back perspective view thereof;

FIG. 4 is a front view thereof;

FIG. 5 is a back view thereof;

FIG. 6 is a right side view thereof;

FIG. 7 is a left side view thereof;

FIG. 8 is a top view thereof; and,

FIG. 9 is a bottom view thereof.

The broken lines shown in the drawings represent portions of the top shell for helmet that form no part of the claimed design.
